Primary Examiner — Susan Moon Lee(74) *Attorney, Agent, or Firm* — Flaster/Greenberg PC(57) **CLAIM**

The ornamental design for a brush head skirt, as shown and described.

DESCRIPTION

FIG. 1 shows a front and right perspective view of a brush head skirt;
FIG. 2 shows a right side cut in half view angled slightly back to front of a brush head skirt;
FIG. 3 shows the view of FIG. 2 not cut in half;
FIG. 4 shows a right side cut in half view of a brush head skirt;
FIG. 5 shows a right side view of a brush head skirt;
FIG. 6 shows a top view of a brush head skirt;
FIG. 7 shows a bottom view of a brush head skirt;
FIG. 8 shows a left side view of a brush head skirt;
FIG. 9 shows a front side view of a brush head skirt; and,
FIG. 10 show a back side view of a brush head skirt.
The elements shown in broken line depict environment for purposes of illustration, and form no part of the claimed design.

1 Claim, 5 Drawing Sheets## Related U.S. Application Data

a continuation-in-part of application No. 14/447,974, filed on Jul. 31, 2014, now Pat. No. 9,635,927, which is a continuation-in-part of application No. 29/485, 705, filed on Mar. 21, 2014, now Pat. No. Des. 793,090.
